(57) **CLAIM**

The ornamental design for a receptacle holder, as shown and described.

DESCRIPTION

FIG. 1 is a top front perspective view of a receptacle holder showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the receptacle holder that form no part of the claimed design. The dot-dash-dot broken lines in FIG. 7 show the boundaries that form no part of the claimed design.
